DELIVERY MECHANISM FOR PRINTING PRESSES

William K. Eckhard, Westerly, R. I., assignor to
 C. B. Cottrell & Sons Company, Westerly, R. I.,
 a corporation of Delaware

Application June 9, 1936, Serial No. 84,269

6 Claims. (Cl. 271—68)

My invention is directed to improvements in flat sheet deliveries for web printing presses whereby suction means may be effectively employed for taking the sheets from the sheet forwarding means and depositing them in one or more piles.

The object of my invention is to provide suction means operable to contact with the tail end of a sheet to depress, stop and release the sheet and thereby prevent the tendency to mark or marr the sheets during their delivery. This marking or marring of the sheets is liable to happen where mechanical means are employed for gripping the upper and undersides of the tail end of the sheet for delivering it and this is particularly true where the sheets are printed without tail margins as is frequent at the present time.

My invention comprises, generally, suction means arranged to be brought into contact with the underside of the tail end of a sheet as it is forwarded to its delivery point, depress the sheet and stop its travel and then release the sheet to permit it to fall without forward momentum onto its pile.

My invention more particularly comprises a plurality of suction nozzles arranged to travel in an endless path, first upwardly and forwardly into contact with the sheet, then downwardly to depress, stop and release the sheet, and finally rearwardly, to complete their cycle.

A practical embodiment of my invention is represented in the accompanying drawings in connection with a two pile flat sheet delivery for a rotary web printing press.

Fig. 1 represents in diagram a side elevation of so much of the web printing press and sheet delivery as includes my invention.

Fig. 2 represents on a larger scale a diagram showing four different positions of the suction means in its endless travel.

Fig. 3 represents an outside view of the valve for controlling the suction means, the parts being shown in the positions they assume at the start and finish of the contact of the suction means with the underside of the tail end of the sheet before it is depressed.

Fig. 4 represents a similar view with the parts in the positions they assume when the suction means has moved downwardly to depress, stop and about to release the sheet.

Fig. 5 represents a similar view showing the parts in the positions they assume when the suction means is cut off and open to atmosphere at the beginning of its cycle.

Fig. 6 represents a detail end view of the cam

mechanism for controlling the movement and operation of the suction means.

Fig. 7 represents a detail side view of the same.

Fig. 8 represents a detail vertical longitudinal section showing one of the suction nozzles and its operating parts in the positions they assume as the suction nozzles are about to depress and stop the travel of the sheet.

Fig. 9 represents an end view of the same.

Fig. 10 represents a view similar to Fig. 8 with the parts in the positions they assume as the suction nozzles are about to release the tail end of the sheet.

Fig. 11 represents a similar view with the parts in the positions they assume as the suction nozzles have returned to complete their cycle.

Fig. 12 represents a detail plan view of one of the suction nozzles.

Fig. 13 represents a longitudinal vertical section through the same.

Fig. 14 represents a detail side elevation of the gear trains connecting the inner and outer sets of suction nozzles with each other and with their drive.

Fig. 15 represents a detail top plan view of the same.

The rotary web printing press is herein shown as arranged to print in four colors on one side of the web, the impression cylinder being denoted by 1 and the form cylinders by 2, 3, 4, 5. The web is denoted by 6 and the sheets cut from the web are denoted by 7. The pair of rotary coacting cutters for severing the sheets from the web are denoted by 8, 9.

The inner horizontally disposed carrier 10 travels in an endless path and it is driven at the surface speed of the press.

The outer horizontally disposed carrier 11 travels in an endless path and it is driven at a surface speed somewhat in excess of the surface speed of the press and the inner endless carrier.

A rotary transfer carrier 12 is interposed between the outer end of the inner endless carrier 10 and the inner end of the outer endless carrier 11.

Side grippers 13 on the inner endless carrier 10 serve to advance a web through the coacting rotary cutters 8, 9 to the head grippers 14 on the rotary transfer carrier 12, which head grippers in turn transfer the sheets cut from the printed web to the head grippers 15 on the outer endless carrier 11.

A horizontally disposed delivery carrier 16 travels in an endless path around the inner and outer piles 17 and 18, which delivery carrier 55

travels at the surface speed of the outer endless carrier 11. This endless delivery carrier 16 is provided with spaced sheet supporting surfaces 19 arranged in the travel of the carrier to pass between the outer endless carrier 11 and the tops of the piles 17 and 18.

Suction means are employed for contacting with the undersides of the tail ends of the sheets as the sheets are forwarded by the grippers 15 10 of the endless delivery carrier 11 to points over their respective delivery piles 17 and 18, which suction means operate to take the sheets from the endless delivery carrier and deposit them upon their respective piles.

15 Each suction means is constructed, arranged and operated as follows: A plurality of suction nozzles 20 (one only and its operating parts being shown and specifically described herein) are located in line across the delivery immediately 20 back of their delivery pile. Each of these nozzles 20 is caused to travel in an endless path to complete its cycle of operation, as follows: The horn 21 of the suction nozzle 20 is provided with a slide 22 which reciprocates on a tilting support 23 which is pivoted on its rear end at 24 to an uprising bracket 25 of the frame. This slide 22 is operatively connected by a rod 26 to a lever arm 27 fixed to a rock shaft 28. This shaft is rocked from a cam 29 fixed on a rotary shaft 30, through the lever arm 31, connecting rod 32, lever arm 33 and lever arm 34. This lever arm 34 carries a stud or roller 35 which is yieldingly held in contact with the face of the rotary cam by the spring means 36.

35 The tilting support 23 is operatively connected by a rod 37 to a lever arm 38 fixed to a rock shaft 39. This shaft is rocked from a cam 40 fixed on the rotary shaft 30, through the lever arm 41 which carries a stud or roller 42 yieldingly held in contact with the face of the cam 40 by the spring means 43.

The means for applying and cutting off the suction is as follows: A valve is located in the suction line, one portion 44 of which line leads 45 to a suitable pump (not shown herein) and the other portion 45 of which line leads across the delivery and is connected to the suction nozzles through flexible branch lines 46.

This valve comprises inner and outer stationary members 47 and 48 and an interposed rotary member 49 fixed to the rotary cam shaft 30 through the pin 50, hub 51 and set screw 52.

The inner stationary member 47 has the suction line ports 53, 54, and suction line portions 55, 44, 45. The outer stationary valve member 48 has the atmospheric port 55. The interposed rotary valve member 49 has an elongated concentric port 56 having an offset portion 57, which port will, in the movement of the rotary valve member, open communication between the portions 44, 45 of the suction line, to apply suction to the nozzles 20 and at the proper time open the nozzle portion 45 of the suction line through the port 55 and offset portion 57 of the port 56, 65 to atmosphere.

It will be understood that while there may be as many suction nozzles as desired, it is only necessary to employ one pair of cams 29 and 40 for each set.

70 Where a double pile delivery is employed, the inner and outer cam shafts 30 are each geared to a longitudinally disposed shaft 58 through a train of gears 59 to 68 inclusive. The shaft 58 is geared to the shaft 69 of the speed-up rotary carrier 12 through the train of gears 70 to 74

inclusive. This shaft 69 may be driven from the shaft 75 at the outer end of the inner endless carrier 10 through the gears 76, 77, to cause the rotary carrier 12 to travel at a considerably greater surface speed than that of the said endless carrier 10. The gear 73 is fast on the shaft 78 at the inner end of the outer endless carrier 11 so that this carrier is caused to travel at substantially the same surface speed as the rotary carrier 12. It will also be understood that the 10 endless delivery carrier 16 may be driven at substantially the same surface speed as that of the endless carrier 11 by providing a gear 79 which is driven from the gear 73 through the gears 80 and 81.

15 Cams 82 and 83 are positioned to open alternate head grippers 15 on the outer endless carrier 11 as their sheets reach points over their respective inner and outer delivery piles 17 and 18.

20 In operation: as the printed web leaves the press it is engaged by successive side grippers 13 of the inner endless carrier 10 and advanced through the rotary cutters 8, 9 which sever the sheets 7 from the web. As the sheets are severed 25 the head grippers 14 on the rotary carrier 12 grasp successive sheets, speed up their travel and transfer them to successive sets of head grippers 15 on the outer endless carrier 11. These head grippers 15 advance the sheets outwardly over 30 the inner and outer piles, the sheets at the same time being supported by successive sheet supporting surfaces 19 of the endless delivery carrier 16, which surfaces travel along with and under the outer endless carrier 11.

35 The alternate head grippers 15 are opened by their respective cams 82 and 83 to release the leading ends of their respective sheets as the sheets reach positions over the inner and outer piles 17 and 18 respectively.

40 As the leading ends of the sheets are released by the grippers 15 of the endless delivery carrier 11 the suction nozzles 20 which have been moved upwardly and forwardly into contact with the undersides of the tail ends of their respective 45 sheets are then moved downwardly to depress the tail ends of the sheets and stop the outward travel of the sheets. The suction nozzles will retain control of the sheets until the supporting surfaces 19 of the endless carrier 16 pass out from 50 under the sheets. The suction nozzles are then caused to release the sheets by the movement of the suction control valve, and thus permit the sheets to be deposited upon their respective piles. The suction nozzles are then moved rearwardly to 55 complete their cycle of movement and operation.

60 While I have shown the invention in connection with a double pile sheet delivery it is obvious that the cam mechanism can be successfully used to operate a single set of suction nozzles for a single pile delivery. It will also be understood that while I have described a gear mechanism for operatively connecting the several parts, any other suitable mechanism may be used for this 65 purpose.

66 The delivery, except the suction means and its operating mechanism, shown, described, but not claimed herein, forms the subject matter of the copending application of Howard M. Barber, filed November 14, 1935, Serial No. 49,684.

70 It is evident that various changes may be resorted to in the construction, form and arrangement of the several parts without departing from the spirit and scope of my invention, and hence 75

I do not intend to be limited to the particular embodiment herein shown and described, but

What I claim is:

1. A flat sheet delivery comprising a sheet delivery carrier traveling in an endless path, a suction line, suction nozzles located within the path of the endless delivery carrier and arranged to be brought upwardly into contact with the undersides of the tail ends of the sheets as the sheets are being forwarded by the endless delivery carrier, and coacting mechanisms arranged to move the nozzles in endless paths to engage, depress and release the sheets.
2. A flat sheet delivery comprising a sheet delivery carrier traveling in an endless path, a suction line, suction nozzles located within the path of the delivery carrier and arranged to be brought upwardly into contact with the undersides of the tail ends of the sheets as the sheets are being forwarded by the endless delivery carrier, and coacting mechanisms arranged to move the nozzles in endless paths to engage, depress and release the sheets, said mechanisms including a control valve in the suction line.
3. A flat sheet delivery comprising a sheet delivery carrier traveling in an endless path, a suction line, suction nozzles located within the path of the delivery carrier and arranged to be brought upwardly into contact with the undersides of the tail ends of the sheets as the sheets are being forwarded by the endless delivery carrier, and coacting mechanisms arranged to move the nozzles in endless paths to engage, depress and release the sheets, said mechanisms including a rotary shaft and a control valve in the suction line, mounted on said shaft.
4. A flat sheet delivery comprising a sheet delivery carrier traveling in an endless path, a

suction line, suction nozzles located within the path of the delivery carrier and arranged to be brought upwardly into contact with the undersides of the tail ends of the sheets as the sheets are being forwarded by the endless delivery carrier, and coacting mechanisms arranged to move the nozzles in endless paths to engage, depress and release the sheets, said mechanisms including a rotary shaft driven from the endless delivery carrier and a control valve in the suction line, 10 mounted on said shaft.

5. A flat sheet delivery comprising a sheet delivery carrier traveling in an endless path, a suction line, suction nozzles located within the path of the delivery carrier and arranged to be 15 brought upwardly into contact with the undersides of the tail ends of the sheets as the sheets are being forwarded by the endless delivery carrier, and coacting mechanisms arranged to move the nozzles in endless paths to engage, depress 20 and release the sheets, said mechanisms including a rotary shaft, a control valve in the suction line and two cams.

6. A flat sheet delivery comprising a sheet delivery carrier traveling in an endless path, a suction line, suction nozzles located within the path of the delivery carrier and arranged to be brought upwardly into contact with the undersides of the tail ends of the sheets as the sheets are being forwarded by the endless delivery carrier, and 25 coacting mechanisms arranged to move the nozzles in endless paths to engage, depress and release the sheets, said mechanisms including a rotary shaft, a control valve in the suction line and two cams, the control valve and the two cams 30 being all mounted on said rotary shaft.

WILLIAM K. ECKHARD.
